US00D533343S

(12) **United States Design Patent** (10) Patent No.: **US D533,343 S**
(45) Date of Patent: **** Dec. 12, 2006**

(54) **TOOL SHEATH**

(75) Inventor: **Donald Gringer**, New York, NY (US)

(73) Assignee: **Allway Tools, Inc.**, Bronx, NY (US)

(**) Term: **14 Years**

(21) Appl. No.: **29/236,907**

(22) Filed: **Aug. 24, 2005**

(51) LOC (8) Cl. **03-01**

(52) U.S. Cl. **D3/228**

(58) Field of Classification Search **D3/228, D3/226, 224, 220, 218; 224/904, 251, 253, 224/676-677, 673**

See application file for complete search history.
